[57] CLAIM

The ornamental design for a motorcycle tire, as shown and described.

DESCRIPTION

FIG. 1 is a front elevational view of a motorcycle tire embodying our design, the rear elevational view being a mirror image thereof, it being understood that the tread pattern repeats uniformly throughout the circumference of the tire;

FIG. 2 is an enlarged fragmentary front elevational view of the motorcycle tire in FIG. 1;

FIG. 3 is a perspective view of the motorcycle tire in FIG. 1; and,

FIG. 4 is a right elevational view of the motorcycle tire in FIG. 1, the left elevational view being a mirror image thereof.
